UNITED STATES PATENT OFFICE.

GEORGE C. CHRISTNER, OF RIVESVILLE, WEST VIRGINIA.

CROSSTIE.

Application filed March 8, 1927. Serial No. 173,721.

This invention pertains to a cross tie for railroads, and particularly refers to a cross tie adapted for use with the railroads employed in mines and similar places, the object being to provide such a cross tie which will hold the ends of the rails together without slipping and which will, however, permit the ready adjustment of the gage of the track while preventing spreading of the rails.

The invention also seeks to provide a device of this kind which will remain in the position in which it is placed.

The invention also has the advantages that the mine cars are made much lower, making the loading of the cars more easily accomplished. Also there is the advantage that there are no obstructions between the rails so that if horses or mules are used as motive power for the cars there will be no obstruction in their path. Further, there is produced by the present invention a tie which is practically immovable when secured in position, which is of importance since there is no ballast employed between the rails upon which mine cars operate.

Referring to the drawings:—

Figure 1 represents a perspective of the tie forming the subject matter of the present invention,

Figure 2 shows a cross section through the tie and rails,

Figure 3 is a horizontal section taken on line 3—3 of Fig. 2,

Figure 4 shows the invention applied to a rail, the so called "fish plate" being removed; and

Figure 5 is a detail perspective of the fish plate used.

It will be seen from the drawings that the tie is constructed of two rail joint clamp portions and cooperative parts exactly similar, united by a cross piece 10, therefore only one of these clamps will be described, it being considered that the other is an exact duplicate thereof. The invention consists of a cross piece 10 having each of its opposite end portions upwardly and inwardly bent, as at 11, to form an inwardly opening channel for the seating within the same of the outer adjacent flange portions of the adjacent ends of the rails *a* and *b*, and then is bent beyond the channel in a manner to provide a vertical portion or wall 12 lying parallel to the outer faces of the web portions of the rails *a* and *b*. The cross piece or

tie 10 is preferably formed with strengthening flanges 13 depending from its opposite side edges, and coextensive with the latter prior to the forming at its opposite ends of the channels 11 and the vertical walls 12. A fish plate, or the like, 14 is preferably interposed between the outer faces of the web portions of the adjacent rail ends *a* and *b*, and the inner opposed face of the vertical wall 12 of the cross piece or tie 10. When properly positioned on the cross piece or tie 10, the adjacent ends of the rails *a* and *b* rest upon its upper face, with their abutting point disposed in the plane of the longitudinal center thereof. The length of the cross piece 10 between the channels 11 and the vertical wall portions 12 is to be made to correspond to a predetermined gauge of track, and the opposite track rail sections will be accurately spaced to the selected gauge, when complementary rail ends are abutted against the fish plates 14 placed at the inner sides of the vertical portions 12 of the cross piece or tie 10.

A cooperative clamp member is provided for each end of the cross piece or tie 10, and this comprises a vertical portion 15, inwardly through which is threaded a screw or the like 16, which, when moved inwardly toward the rail joint, bears against the outer face of the vertical end portion 12 of the cross piece or tie 10. This vertical portion 15 rises from the outer connected edge of a bottom wall 17, which extends inwardly beneath the adjacent end of the cross piece or tie 10, and has a slotway 18, extending through the same in line with the longitudinal center of the cross piece or tie 10, engaged by a guide member 19, depending from the under side of the latter. This slot and guide arrangement allows for relative movement of the cross piece or tie 10 and the clamp into and out of rail joint clamping or securing engagement. A central portion of the inner edge of the bottom wall 17, of the clamp member, is cut away, as at 20, to provide oppositely disposed portions, each bent upwardly and outwardly toward the vertical wall 15 into the form of hooks or lugs 21. These hooks or lugs 21 are spaced apart sufficiently to project upwardly at the opposite sides of the cross piece or tie 10, and are to be engaged over the inner flange portions of the adjacent ends of the rails *a* and *b*. The clamp member is also flanged, as at 22, at the opposite side edges

of the vertical portion 12 and the bottom portion or wall 17 thereof for reinforcement or strengthening purposes.

Each of the fish plates 14 is preferably formed to provide a pair of outwardly directed lugs 14', formed angularly of the opposite ends of its lower edge, and the same engage the opposite side edges of the bent portions of the cross piece or tie 10 forming the channels 11, while a second pair of lugs 14'' are projected inwardly from the opposite end edges of the fish plate 14 for engagement in apertures formed in the rail portions *a* and *b* for their reception. This coupling of the rail ends together through the medium of the lug connections of the fish plates therewith, prevents any possible relative longitudinal movements of the rail sections, other than which may be incident to temperature changes, when the fish plates will have practically the same expansion and contraction factors as that of the rails themselves. It is to be noted that a nut 23 is threaded onto the clamp screw 16, but is abutted against the inner face of the vertical wall 15 of the clamp, when the screw 16 is moved into clamping relation against the outer face of the vertical end or wall portion 12 of the cross piece or tie 10, so as to prevent accidental loosening up of the screw 16 throughout its operative use.

From the foregoing, it will be readily obvious that when it is desired to lay a track, the screws 16 will be threaded to outwardly disposed positions in the vertical walls 12 of the oppositely arranged clamp members, and the latter will then be moved inwardly on the complementary ends of the cross piece or tie 10. This action will space the hooks or lugs 21, on each clamp, inwardly from the vertical walls 12 and readily allow for the rail ends *a* and *b* to be positioned on the cross piece or tie 10, with their outer flange portions engaged in the channel 11, and the interposing of the fish plates 14 between the web portions of these rail ends and the vertical end walls 12. Now, by turning the screws 16 inwardly until their inner ends press against the vertical walls 12 of the cross piece or tie 10, the clamp members will be drawn or forced outwardly of the opposite ends of the latter, and the hooks or lugs 21 will be tightly engaged over the inner flange portions of the rail ends *a* and *b* when the parts will be securely clamped together, and any and all relative movement of these parts, under any and all conditions of use, will be positively prevented, until it is desired to separate the parts for repair, replacement or removal.

Without further description, it is thought that the features and advantages of the invention will be readily apparent to those skilled in the art, and it will of course be understood that changes in the form, pro-

portion and minor details of construction may be resorted to, without departing from the spirit of the invention or its scope as claimed.

I claim:

1. A rail tie comprising a cross member disposed beneath the abutting ends of adjacent rail sections and having upwardly directed end portions engaging the outer sides of the adjacent rail ends, fish plates interposed between the upwardly directed end portions of said cross member and the opposed sides of the adjacent rail ends, and clamping means mounted for relative movement on the ends of said cross member and having outwardly extending portions engaging the inner sides of the adjacent rail ends outwardly of the opposite side edges of the cross member and cooperative with the said rail engaging portions of the said cross member for securing the adjacent rail ends therebetween. 70

2. A rail tie comprising a cross member disposed beneath the abutting ends of adjacent rail sections and having upwardly directed end portions engaging the outer sides of the adjacent rail ends, fish plates interposed between the upwardly directed end portions of said cross member and the opposed sides of the adjacent rail ends and having portions engaging openings in the latter, and clamping means mounted for relative movement on the outer ends of said cross member and having outwardly extending portions engaging the inner sides of the adjacent rail ends at the opposite sides of the cross member and cooperative with the said rail engaging portions of said cross member for securing the adjacent rail ends therebetween. 80

3. A rail tie comprising a cross member disposed beneath the abutting ends of adjacent rail sections and having upwardly directed end portions engaging the outer sides of the adjacent rail ends, fish plates interposed between the upwardly directed end portions of said cross members and the opposed sides of the adjacent rail ends and having portions engaging openings in the latter, clamping members mounted for relative movement on the outer ends of said cross member and having outwardly extending portions engaging the inner sides of the adjacent rail ends, and means carried by said clamping members and cooperative with the outer sides of the upwardly directed portions of the said cross member for moving the said clamping members outwardly of the said cross member for the clamping of the adjacent rail ends and the said fish plates securely between the said upwardly directed portions of the said cross member and the inner rail end engaging portions of the said clamping members. 90

4. A rail tie comprising a cross member

- disposed beneath the abutting ends of adjacent rail sections and having upwardly directed end portions engaging the outer sides of the adjacent rail ends, fish plates disposed between the outer sides of said rail sections and the opposed end portions of said cross member, clamping members mounted for relative movement on the outer ends of said cross member and having outwardly extending portions engaging the inner sides of the adjacent rail ends, means carried by said clamping members and cooperative with the outer sides of the upwardly directed portions of the said cross member for moving the said clamping members outwardly of the said cross member for the clamping of the adjacent rail ends and the said fish plates securely between the said upwardly directed portions of the said cross member and the inner rail end engaging portions of the said clamping members, and cooperative guide means connecting the said clamping members in position on the complementary ends of said cross member.
- 10 5. A rail tie comprising a cross member extending between and disposed beneath the rail sections at the opposite sides of a track and having upwardly directed end portions engaging the outer sides of the rails, clamping means mounted for relative movement on the opposite ends of said cross member and having outwardly extending portions engaging the inner sides of the rails outwardly of the opposite side edges of the cross member and cooperative with the said rail engaging portions of said cross member for securing the rails therebetween, and means for securing said clamping means in their operative positions.
- 15 6. A rail tie comprising a cross member extending between and disposed beneath the rail sections at the opposite sides of a track and having upwardly directed end portions engaging the outer sides of the rails, clamping means mounted for relative movement on the opposite ends of said cross member and having outwardly extending portions engaging the inner sides of the rails outwardly of the opposite side edges of the cross member and cooperative with the said rail engaging portions of said cross member for securing the rails therebetween, and means for securing said clamping means in their operative positions.
- 20 7. A rail tie comprising a cross member extending between and disposed beneath the abutting ends of adjacent rail sections at the opposite sides of a track and having upwardly directed end portions engaging the outer sides of the adjacent rail ends, clamping means mounted for relative movement on the opposite ends of said cross member and having outwardly extending portions engaging the inner sides of the adjacent rail ends outwardly of the opposite side edges of the cross member and cooperative with the said rail engaging portions of said cross member for securing the adjacent rail ends therebetween, and means for securing said clamping means in their operative positions.
- 25 8. A rail tie comprising a cross member disposed beneath the abutting ends of adjacent rail sections and having upwardly directed end portions engaging the outer sides of the adjacent rail ends, fish plates interposed between the upwardly directed end portions of said cross members and the opposed sides of the adjacent rail ends and having portions engaging openings in the latter, clamping members mounted for relative movement on the outer ends of said cross member and having outwardly extending portions engaging the inner sides of the adjacent rail ends, means carried by said clamping members and cooperative with the outer sides of the upwardly directed portions of the said cross member for moving the said clamping members outwardly of the said
